UNITED STATES PATENT OFFICE.

FAUSTIN J. SOLON, OF TOLEDO, OHIO, ASSIGNOR TO THE OWENS BOTTLE COMPANY, OF TOLEDO, OHIO, A CORPORATION OF OHIO.

CONTAINER AND HOLDER THEREFOR.

Application filed July 1, 1921. Serial No 481,762.

To all whom it may concern:

Be it known that I, FAUSTIN J. SOLON, a citizen of the United States, residing at Toledo, in the county of Lucas and State of Ohio, have invented new and useful Improvements in Containers and Holders Therefor, of which the following is a specification.

My invention relates to containers, which may be in the form of glass jars or wide mouth bottles, adapted to hold various small articles, and to supporting devices in which said containers are mounted.

The invention is adapted to a great variety of uses, as for example, in stock rooms of machine shops or factories, for holding small parts such as bolts, screws, springs, washers, etc.—in stores, for holding and displaying candies and numerous other articles of merchandise,—in the home, for storing various articles of food, etc. The above are given merely as examples of the various uses for which the invention is adapted.

An object of the invention is to provide a container of the character indicated in combination with a tilttable holder in which the container is removably held, and a supporting frame-work in which the holder is mounted, whereby the holder with its container may be readily tilted into position for removing articles from the container or for replenishing them, together with suitable means for automatically closing the container when it is returned to its normal upright position.

Other objects of the invention will appear hereinafter and various features of novelty are set forth in the following specification which will be understood in connection with the accompanying drawings wherein;—

Figure 1 is a front elevation, partly broken away, of a device constructed in accordance with my invention.

Figure 2 is an end view of a portion of the same.

Figure 3 is a part sectional end view of a modified form of support for the containers.

Figure 4 is a section at the line 4—4 on Figure 3.

Figure 5 is a sectional end elevation of the apparatus shown in Figure 1, one of the container supports being tilted.

Figure 6 is a fragmentary plan view of one end of a holder and adjacent parts.

Figure 7 is a front elevation of the same. Figures 8 to 11 inclusive, illustrate a modified construction in which there are individually tilttable holders for the several containers. Figure 8 is a sectional elevation showing a container in normal position. Figure 9 is a similar view showing the container tilted. Figure 10 is a part sectional front elevation. Figure 11 is a fragmentary plan view of a container and its holder.

Figures 12 to 14 illustrate a further modification. Figure 12 shows the holder in transverse section, and also indicates in broken lines a container in normal position in the holder. Figure 13 is a plan view of the same. Figure 14 is a fragmentary view of one of the holders.

Figure 15 is a plan showing a further modification of the holder.

Referring particularly to Figures 1, 2, 5, 6 and 7, a rack or frame-work is provided which may be made of angle bars of standard construction. These comprise front and rear upright end bars 20 and 21, lower horizontal front and rear bars 22 and 23, additional front bars 24, lower transverse end bars 26, and transverse end bars 27, opposite the bars 24. Diagonal brace rods 29 may be provided at the rear of the frame-work, if desired. The frame-work may be built to any desired height, depending on the number of rows of containers it is desired to support therein.

The containers 31 are carried in tiltably mounted holders 32. Each holder comprises a base bar 33 extending lengthwise of the frame and having its ends 34 bent upward to vertical position. Front and rear bars 35 and 36 respectively extend parallel with the bar 33 and have their ends bent and secured to the upright ends 34 of the bar 33. The bars 33, 35 and 36 are suitably spaced to form pockets or compartments to receive the containers 31. The front bar 35 is formed at regular intervals with re-entrant portions or bends 37 to space the containers 31 and hold them against movement lengthwise of the holders.

Rock shafts 40 journalled in the ends of the frame have fixed thereto angle bars or brackets 41 secured to the bars 33 by bolts 42. This permits the holder to be swung forward to tilt the containers from their normal upright position to the forwardly inclined position shown at the lower part of

Figure 5. A finger piece 43 may be attached to the bar 35 for tilting the holder. Adjustable stops 44 and 45 limit the forward and return movements of the holder respectively.

The holder may be held by spring pressure both in its tilted and normal position. For this purpose a coil spring 46 is mounted on a rod 47 which has a sliding connection 10 with a fulcrum pin 48, said rod being connected by a pivot 49 with a rock arm 50 on the shaft 40. The spring 46, held under compression between the fulcrum pin 48 and a stop 52 on the rod 47, tends to move 15 said rod endwise toward the arm 50. In this manner spring pressure is applied to hold the holder in its tilted position, as seen in the lower half of Figure 5, and also to hold it when returned to upright position, as 20 shown for example in Figure 2.

The containers 31, as shown, consist of glass jars, although they may be made of other materials. The upper end or lip 53 of each container is inclined to the horizontal 25 so as to bear squarely against an inclined cover or closure 54. This, as shown in Figures 1 and 5, may be made of felt, cork or other suitable material mounted in a holder 55 extending lengthwise of the frame, said holder 30 comprising spring arms 56 by which it is secured to the frame. It will be seen that with this construction the cover 54 is held with a yielding pressure against the mouths of the containers, forming a close fit. The 35 open ends of the containers being inclined, as shown, permits them to readily slide into position beneath the cover 54. This is true not only of the construction shown, but adapts them for use with a cover such as 54 40 when the latter is arranged over an ordinary shelf or horizontal support so that the containers are closed by simply sliding them back into position on such support.

As shown particularly in Figures 2 and 45 5, provision is made for adjusting the ends bars 27 of the frame vertically, thereby adjusting the covers 54 to containers of different lengths. This adjustment is provided by vertical slots 58 in the upright frame 50 members through which clamping bolts 59 extend. As shown in Figure 5, a slot 60 is also provided for the fulcrum pin 48 above the bar 27 so that said pin may be adjusted with the corresponding holder. Provision 55 may be made for adjusting the front and rear bars 35 and 36 toward and from each other to fit containers of different sizes. The means for such adjustment is shown in Figures 3 and 4, wherein the ends of said 60 bars are provided with slots 62. Clamping bolts 63 extend through said slots and through the uprights 34.

Figures 8 to 11 illustrate a modified construction in which the containers are carried 65 in individual holders, permitting each

container to be tilted independently of the others. The holders are arranged in a sheet metal cabinet comprising individual sections or units. Each unit comprises a base 64, back 65 and top 66, all of which 70 may be formed from a single piece of sheet metal. Any desired number of these sections may be mounted one above another. Locking strips 67 on each section are adapted to fit in sockets 68 in the section beneath, 75 permitting said sections to be readily assembled and securely held in assembled relation. The back 65 may be formed with strengthening ribs 69. Each container 31 is supported in a holder 70 which is made of sheet metal and comprises a band extending horizontally to embrace three sides of the container. The holder is formed with an extension 72 which provides a bottom support for the container. The holder is provided with pivot pins or trunnions 73 by which it is mounted for tilting movement. Standards 74 rising from the base 64 provide bearings for the trunnions 73. Each of these standards 74 may have its upper 80 end bent downward as shown so that a single standard provides a bearing for the holders on opposite sides thereof. The standards are also formed with rearward extensions 77 secured to the wall 65. The arm 72 of the holder terminates in a loop 71 which acts as a stop to arrest the container in its tilted position and owing to its resiliency, also serves as a friction gripping device to hold the container in such position. Individual covers or stoppers 75 are provided for the containers. These may be made of sheet metal stamped or shaped to provide a convex cover-piece to form a close fit with the mouth of the container, an extension 76 forming a spring connection with the top 66 so that the cover will be held in position with a yielding pressure and will also yield to permit the container to swing 100 to and from its closed position.

The tilting movement of the container 31, as indicated in Figure 9, is limited by the end 71 of the extension 72 engaging the part 77. The bottom of the container may be rounded so that it cannot be readily stood on a flat support, thereby reducing any liability of the container being inadvertently left out of its carrier when it has been removed for any purpose.

Figures 12 to 14 inclusive illustrate a further modification of the holder. In this construction the containers 31 are supported by individual clips or gripping devices 80 mounted in a supporting bar 81 located 115 at the rear of the containers and extending lengthwise of the frame. The ends 82 of said bar extend forwardly and are secured by bolts 83 to the uprights 34, slots 84 being provided in said ends to receive the bolts 120 83, thereby permitting forward or rearward

- adjustment of the holders. The clips 80 are formed of spring sheet metal and are provided with slots 85 to receive the bar 81. When the clip 80 is removed from the bar 81 its two arms containing the slots 85 are spread by the resiliency of the clip to the Figure 14 position. To apply the clip to the bar it is first compressed so that the slotted portions are parallel, as shown in 10 Figure 13, permitting the clip to be positioned on the bar 81. The resiliency of the clip will then tend to spread said arms and cause them to bind on the bar 81, thereby holding the clip against displacement along 15 the bar. When the container 31 is placed in position in a clip, it may be spread still further, which will increase the gripping effect on the bar 81 and also securely hold the container.
- 20 Figure 15 shows a further modification in which clips 86 are provided of such shape that each container 31 is held between the arms of two adjacent clips.
- Modifications may be resorted to within 25 the spirit and scope of my invention.
- What I claim is:
1. The combination of a rack or frame, a holder mounted thereon, a container carried by said holder, said holder being tilttable about an axis beneath the container to swing the container from an upright position, to a forwardly and upwardly inclined position, means to arrest the container at said positions, the container having an inclined open 30 upper end, and an inclined closure device positioned to close the container as the latter swings from a tilted to an upright position.
  2. The combination of a rack or frame, a holder tiltably mounted thereon, a container having an open upper end, said container being carried by said holder, said holder being tilttable to swing the container forward from an upward position to a forwardly and up- 35 wardly inclined position, spring actuated means to yieldingly hold the container in its forward tilted position, and automatic means to close the container when it is returned to upright position.
  3. The combination of a rack or frame, a holder tiltably mounted thereon, a container carried by said holder, said holder being tilttable to swing the container to and from an upright position, and a spring actuated device to hold the container in its holder in both upright and tilted position. 50
  4. The combination of a supporting frame, a holder mounted thereon and extending lengthwise thereof, said holder providing a series of compartments adapted to receive individual containers, means to tilt said holder forward about a horizontal axis below the containers and thereby swing the containers forward from an upright to a forwardly and upwardly inclined position, and a stop to arrest the holder with the containers in said 55 inclined position.
  5. The combination of a supporting frame, a holder mounted thereon and extending lengthwise thereof, said holder providing a series of compartments adapted to receive individual containers, means to tilt said holder forward about a horizontal axis below the containers and thereby swing the containers forward from an upright to a forwardly and upwardly inclined position, 60 a stop to arrest the holder in its tilted position, and a closure device extending lengthwise of the supporting frame and positioned to engage and close the open upper ends of the containers when the latter are 65 swung to upright position.

Signed at Toledo, in the county of Lucas and State of Ohio, this 29th day of June, 1921.

FAUSTIN J. SOLON.
